(57) CLAIM

The ornamental design of a transfer tape holder, as shown and described.

DESCRIPTION

FIG. 1 is a top view of our transfer tape holder;
FIG. 2 is a bottom view thereof;
FIG. 3 is a front view thereof;
FIG. 4 is a rear view thereof;
FIG. 5 is a right side view thereof;
FIG. 6 is a left side view thereof;
FIG. 7 is a top view of a holder body thereof with the cap removed for ease of illustration;
FIG. 8 is a bottom view of the holder body thereof with the cap removed for ease of illustration;
FIG. 9 is a front view of the holder body thereof with the cap removed for ease of illustration;
FIG. 10 is a rear view of the holder body thereof with the cap removed for ease of illustration;
FIG. 11 is a right side view of the holder body thereof with the cap removed for ease of illustration;
FIG. 12 is a left side view of the holder body thereof with the cap removed for ease of illustration;
FIG. 13 is a top view of a cap thereof shown separately for ease of illustration;
FIG. 14 is a front view of the cap thereof shown separately for ease of illustration;
FIG. 15 is a right side view of the cap thereof shown separately for ease of illustration;
FIG. 16 is a left side view of the cap thereof shown separately for ease of illustration; and,
FIG. 17 is a perspective view thereof as disassembled.
